UNITED STATES PATENT OFFICE.

AMANDA M. BLUNKALL, OF OAKLAND, CALIFORNIA.

COMB.

1,035,411.

Specification of Letters Patent. Patented Aug. 13, 1912.

Application filed June 6, 1911. Serial No. 631,539.

To all whom it may concern:

Be it known that I, AMANDA M. BLUNKALL, a citizen of the United States, residing at Oakland, in the county of Alameda and State of California, have invented a new and useful Comb, of which the following is a specification.

It is the object of the invention to provide a comb having a novel form of hand grip, and a novel form of teeth, the hand grip and the teeth coöperating in operation.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawings,—Figure 1 shows the invention in end elevation, parts being broken away; and Fig. 2 is a front elevation.

Referring to Fig. 2, it will be seen that the comb, in general outline, is sigmoidal or S-shaped in cross section, the comb comprising two falciform or sickle-shaped parts. One of these parts, denoted generally by the numeral 1, is fashioned from celluloid, wood, or any other suitable material of construction. This member 1 includes a flange 2, back-bent to overlie one side of the comb. This flange 2 constitutes a hand grip, when the device is in use. The other falciform member 3 is, like the member 1, a plate, the member 3 provided with a series of teeth 4. The teeth 4 are turned in an opposite direction from the flange 2, and overlie an opposite face of the comb from the flange 2. The member 3 may be secured to the member 1 in any desired manner. In the present instance, the member 1 is grooved along one edge, and the member 3 is formed with a tongue 5, adapted to register in the groove.

When the device is in use, the fingers of

the operator will be engaged with the flange 2, the teeth 4 being drawn through the hair. Owing to the peculiar reverse curvature given to the comb, as appearing in Fig. 1, a secure grip will be afforded by the means of the flange 2, while the teeth 4 will engage properly with the hair.

The member 3 is fashioned entirely from some coloring material, preferably lead. Therefore, when the teeth 4 are drawn through the hair, the hair will be colored, and be darkened in shade. It is to be understood that a soft grade of lead, or other coloring material, is employed in fashioning the member 3, so that the combing operation need not be prolonged unnecessarily, to secure the desired darkening of the hair.

By reason of the fact that the member 3 is fashioned entirely from lead or other coloring material, the teeth 4 will continue to color the hair, until the teeth are entirely worn away. Therefore, the coloring function of the comb will remain, as long as the comb is capable of exercising its combing function.

It will be readily understood that the tongue and groove connection between the members 3 and 1 is such that, although these members are securely held together in operation, they may, nevertheless, be forcibly separated when desired.

Having thus described the invention what is claimed is:

A hair comb having a flange and teeth, the flange and the teeth being turned in opposite directions and into approximate parallelism, to overlie opposite faces of the comb.

In testimony that I claim the foregoing as my own, I have hereto affixed my signature in the presence of two witnesses.

AMANDA M. BLUNKALL.

Witnesses:

OLIVE ARNOLD,
LILLIE BLUNKALL.
